UNITED STATES PATENT OFFICE.

REGINALD ALVIN McCUALEY, OF DORCHESTER, MASSACHUSETTS, ASSIGNOR TO
SAMUEL WARD MANUFACTURING COMPANY, OF BOSTON, MASSACHUSETTS, A
CORPORATION OF MASSACHUSETTS.

COVERING MACHINE.

Application filed June 10, 1924. Serial No. 719,226.

The invention involved herein relates to the manufacture of book covers or other binders or articles of like character. Such articles usually comprise a body portion or 5 portions of thicker or stiffer stock to which a sheet of covering material is attached, the same being drawn over the edges and folded down to form a neat finish.

A characteristic example is a book cover in 10 which the covers or back or both are reinforced by stiff cardboard over which is drawn the outside finishing material such as leather, fabric or paper.

In the finer grades of such book covers it is 15 frequently desired to have round corners. Such corners have given a great deal of difficulty in the covering process and have involved additional steps and additional expense and frequently imperfect work.

20 My present invention contemplates mechanism by which such covers can be formed in a single operation with great rapidity and great accuracy. As illustrative of my invention I will show in the accompanying 25 drawings an embodiment which I have found highly successful in practical use.

Throughout the specification and drawings like reference characters are employed to indicate corresponding parts, and in the 30 drawings:

Figs. 1 and 2 are side and front elevations, respectively, of a press in accordance with my invention.

35 Figs. 3 and 4 are end and side elevations of the forming members in separated relation.

Fig. 5 is a plan view of the lower member.

Fig. 6 a similar view with its top plate removed to expose the folding blades.

40 Figs. 7 and 8 are sectional views showing the raised and lowered positions of the suction plate.

Fig. 9 is a somewhat similar section showing blades projected and the press block down.

45 Fig. 10 is a view similar to Fig. 7 but showing the work as it is released.

Fig. 11 is a fragmentary section showing the adjusting blocks for the suction plate.

50 Figs. 12 and 13 show in plan the positions of the corner blades.

Fig. 14 is a side elevation, and

Fig. 15 a section through a corner blade, and

Figs. 16 and 17 are plan views of the two leaves of the corner blades.

55

Referring to Figs. 1 and 2, I have indicated at 1 the base, at 2 the head, and at 3 the reciprocating slide working in a way 4. It is driven by the main shaft 5 and pulley 6. A usual hand control 7 is provided and 60 a foot pedal 8. A suction device 9 is controlled by a valve 10.

Mounted in the head 2 is an upper press member 11 and a lower member 12 is carried on the bed 1¹ of the base 1. The upper press member generally indicated as 11 consists of a plate 11¹ having a series of blade operating fingers 112 which are for the side blades and 113 which are the corner operating fingers. All these fingers are wedge shaped as 70 at 112¹ or 113¹, these wedging faces acting to force in the edge turning blades which act on the blank B.

The blank B is reinforced by stiffening S of pasteboard or like stock as may be seen 75 in section in Figs. 7 and 9, and which may be variously shaped in plan but generally being an oblong body or sheet with rounded corners as above suggested.

Referring to Fig. 5, it will be seen that 80 the top plate 14 of the base is a rectangular or quadrilateral piece having a central aperture of the size and shape of the particular blank to be operated on. The plates 14 are removable and replaceable to accommodate covers of different sizes or shapes and act as a gage in locating the blank in the machine. The lower member 12 is a block shown in Fig. 6 as exposed by the removal of the upper gage plate 14. It is recessed to a size 85 90 preferably conforming to the area and shape of the blank to be operated on and for that purpose receives a suction plate 15 provided with a hollow stem 16 by which it is operated and through which it is vented. The 95 stem 16 is operably connected to a yoke 17 which by links 18 can be raised or lowered by the pedal 8.

The initial operation is illustrated in the sections shown in Figs. 7 and 8, the assembled blanks B and S glued or cemented together being positioned on the plate 14 over 100

the suction plate 15. The exhaust valve 10 is then opened and the blanks B and S are drawn to and firmly held by the perforated plate 15.

5 The foot lever 8 is then depressed and the plate 15 lowered drawing the blanks B and S down so that the edges of the blank B are laterally upturned as shown in Fig. 8, being turned up against the edges of the stiffening material S.

10 At this point the hand lever 7 is thrown and the press begins to turn over lowering the plate 11. The fingers 112 and 113 now enter their respective openings and engage 15 the lateral blades 18 and corner blades 19 to effect the edge turning motion. These blades are provided with rollers 18^a and 19^a and are adapted to be retracted by springs 18^b and 19^b when the plunger retreats.

20 The lateral blades 18 are simple integral blades but the corner blades are composite and comprise an upper blade 19 which has a V-shaped gathering end and 19^a which has a rounded forming end. Both blades 19 and 19^a are vertically apertured to receive 25 the operating fingers 113. They are each provided in this aperture with a bearing roller 19^a against which the inclined face of the finger works in pushing the slide forward. The two slides have a slight relative movement, the slide 19 being slotted to receive a pin 19^b between which and the wall of the slot is connected a spring 19^c. This permits the slide 19 to move forward 30 over the edge of the stiffening blank S as it turns the edge of the covering blank B over said stiffening blank. Similar bearing rolls 18^b are provided in the lateral blades for contact with their operating fingers 112.

40 In initial position as shown in Fig. 4, the combined blanks B and S are slipped in while the plunger is raised so as to occupy the aperture of the gage plate 14 so as to be properly positioned. In this position it will 45 be noted that the edges of the blanks B which are gaged on the inner edges of this aperture overlie the slides 18 while the main body of the blank rests on the suction plate 15. At this point the valve 10 is turned to 50 its exhausting position and the plate 15 exhausted through its stem 10 thus drawing the combined blanks firmly to its upper surface. The treadle is now depressed lowering the plate 15 to just below the level of 55 the lateral blades 18. This turns up the margin of the blank B vertically so that it stands against the blades 18 with the main body of the blank just below the lower edge of these blades. This position may be accurately adjusted by the wedges 20 which are advanced or retracted by knurled head screws 21 as appears in Figs. 9 and 11. The plunger is now depressed bringing the operating fingers 112 and 113 down through 60 the top plate 14 to advance them to the posi-

tion shown in Fig. 6. The corner blades 19 are timed to advance just after the blades 18 come forward and draw up the material of the sheet B at the corner. The blades 19 and 19^a advance together, the blade 19^a being stopped by the resistance of the stiffening blank B and blade 19 continues to advance a distance represented by the turnover of the leather or other material being turned. When the blades are all in their proper position, the plunger 11 has reached the bottom of its stroke and the plate 11^a which is the size of the finished blank presses firmly down on all these blades thus pinching the covering material firmly over the edge 75 of the blank. The plunger head now retreats, the foot pedal is released to permit the rise of the suction plate 15 to the position shown in Fig. 10 which is its initial position. The air is reversed from exhaust 80 to pressure and the blank released from the suction plate and removed so that the machine is ready for the next blank.

When it is desired to change the style or size of cover to be made the head of the press is lowered bringing the plunger plate to its lower position and the two plates then release, one from its plunger and the other from the bed of the machine and are lifted out together.

The machine can be operated very rapidly and by unskilled labor so that the experienced book binder can be replaced by unskilled help while at the same time production is increased, and more perfect work 100 produced.

Various modifications may be made in details of construction and operation all without departing from the spirit of my invention if within the limits of the appended 105 claims.

What I therefore claim and desire to secure by Letters Patent is:—

1. In a covering device of the class described, a base member, a detachable frame supported above said base, lateral folding blades reciprocably mounted below said frame and disposed about the four sides thereof, reciprocable corner blades disposed between the ends of said slide blades, and a vertically reciprocating press member having a blank pressing portion, and vertically disposed blade operating fingers depending rigidly from said plunger and engageable with the side and corner blades to move the side blades inwardly over the edge of the blank in advance of the corner blades.

2. In a covering device of the class described, a base member, a detachable frame supported above said base, lateral folding blades reciprocably mounted below said frame and disposed about the four sides thereof, reciprocable corner blades disposed between the ends of said slide blades, each comprising a lower curved forming portion

adapted to contact the rounded corner of the blank, and an upper forked gathering portion, and a vertically reciprocating press member having a blank pressing portion, and operating devices carried by said plunger and engageable with the side folders to move them inwardly over the edge of the blank in advance of plunger contact.

3. In a covering device of the class described, a base member, a detachable frame supported above said base, lateral folding blades reciprocably mounted below said frame and disposed about the four sides thereof, reciprocable corner blades disposed between the ends of said slide blades, each comprising a lower curved forming portion adapted to contact the rounded corner of the blank, and an upper forked gathering portion, said base also including a vertically reciprocable suction plate normally disposed in the plane of the folders but compressible below said blade to draw down the blank, and a vertically reciprocating press member having a blank pressing portion, and operating devices carried by said plunger and engageable with the side folders to move them inwardly over the edge of the blank in advance of plunger contact.

4. In a covering device of the class described, a base member, a detachable replaceable frame supported above said base and adapted to position the blanks, lateral folding blades reciprocably mounted below said frame and disposed about the four sides thereof, reciprocable corner blades disposed between the ends of said slide blades, each comprising a lower curved forming portion adapted to contact the rounded corner of the blank and an upper forked gathering portion, and a vertically reciprocating press member having a blank pressing portion, and operating devices carried by said plunger and engageable with the side folders to move them inwardly over the edge of the blank in advance of plunger contact.

5. In a covering device of the class described, a base member, a detachable replaceable frame supported above said base and adapted to position the blanks, lateral folding blades reciprocably mounted below said frame and disposed about the four sides thereof, reciprocable corner blades disposed between the ends of said slide blades, each comprising a lower curved forming portion adapted to contact the rounded corner of the blank and an upper forked gathering portion, said base also including a vertically reciprocable suction plate normally disposed in the plane of the folders but compressible below said blade to draw down the blank, and a vertically reciprocating press member having a blank pressing portion, and operating devices carried by said plunger

and engageable with the side folders to move them inwardly over the edge of the blank in advance of plunger contact.

6. In an edge folder for book covering machines, a base, horizontally disposed side and corner members reciprocably mounted thereon, and a vertically reciprocating plunger having two series of spaced rigid blade operating fingers depending therefrom and engageable with the side and corner blades to move the side blades inwardly over the edge of the blank in advance of the corner blades.

7. A machine for applying fabric and the like to covers, comprising a mold having inwardly slidable side walls for the four straight edges of the cover, and four diagonally disposed slides for the corners of the cover, each of said slides having beneath it a thin slide yieldingly moving with the slide above it to cause it to rest against the corner of the cover while the one above it is moved over the machine.

8. A machine for applying a fabric and the like to covers, comprising a mold having inwardly slidable side walls, and inwardly movable corner slides, each corner slide being in two parts, the under of which is thin and given a concave end to fit against the rounded corner of a cover.

9. A machine for applying fabric and the like to covers, comprising a mold having inwardly slidable side walls, and inwardly movable corner slides, each corner slide being in two parts, the under of which is thin and given a concave end to fit against the rounded corner of a cover, and the upper of which is given a right-angled recess.

10. In a machine for applying fabric and the like to covers, a mold having inwardly slidable side walls formed with vertical slots therein, a plunger having lugs depending therefrom formed with oblique ends for engaging said slots and moving said side walls inward, and springs for retracting said side walls said plunger acting both to fold the fabric edges over the cover by means of said lugs, and to press the fabric down upon the cover.

11. In a machine for applying fabric and the like to covers, a mold having inwardly slidable side walls and inwardly movable corner slides, means for actuating said side walls and corner slides in timed relation to each other, a bottom plate movable vertically in said mold and supports for adjustably limiting the descent of said plate whereby to position said plate slightly below the plane of said side walls and corner slides.

In testimony whereof I affix my signature.

REGINALD ALVIN McCUALEY.
